Patented Nov. 7, 1916.

UNITED STATES PATENT OFFICE.

HAROLD A. ELDREDGE, OF NEWBURYPORT, MASSACHUSETTS.

WINDOW-SCREEN.

1,204,140.

Specification of Letters Patent.

Patented Nov. 7, 1916.

Application filed January 5, 1916. Serial No. 70,486.

To all whom it may concern:

Be it known that I, HAROLD A. ELDREDGE, citizen of the United States, residing at Newburyport, in the county of Essex and State of Massachusetts, have invented certain new and useful Improvements in Window-Screens, of which the following is a specification.

This invention relates to a novel improvement in window screens, and has special reference to screens of that type which are adjustable to fit window frames of varying width.

Primarily, the invention has in view a screen having a novel sliding frame construction whereby the same may be readily collapsed or extended to suit the size of the window and which permits of the use of friction reducing elements in such a manner that the same are housed and protected, and also concealed from view.

Another object of the invention is to provide a screen having a metal frame which is not susceptible of warping or swelling in damp weather, or when wet from rain or the like, thus providing a sectional screen that possesses a maximum efficiency under all service conditions. This feature combined with the novel friction reducing feature above set forth provides for the easy manipulation or sliding movement of the screen section, thus eliminating binding or sticking that usually makes screens of this type difficult to operate.

A further object of the invention is to provide a strong durable screen that is easily and economically manufactured and susceptible of a neat, serviceable, and attractive commercial embodiment.

With the above and other objects in view which will more readily appear as the nature of the invention is better understood, the same consists in the novel construction, combination, and arrangement of parts hereinafter more fully described, illustrated, and claimed.

A preferred and practical embodiment of the invention is illustrated in the accompanying drawings, in which—

Figure 1 is an elevation of my improved screen construction. Fig. 2 is a vertical sectional view thereof on the line 2—2 of Fig. 1 showing the character of the frame parts. Fig. 3 is a horizontal sectional view on the line 3—3 of Fig. 1. Fig. 4 is a detail view of one form of means for prevent-

ing the balls from falling out when both sections are extended to their limit.

Similar reference characters designate corresponding parts throughout the several figures of the drawings.

In carrying out the present invention, it is proposed to utilize an all metallic screen frame which preferably includes the telescoping frame sections 1 and 2 which are 6. slidably interlocked and capable of being adjusted to fit any width of window frame.

Referring to the novel features of the screen section 1, it will be observed that the same essentially includes a hollow up- 70 right post 3 having suitable means 4 for securing one edge of the wire mesh M, and also having connected to its top and bottom corners, in any suitable manner, the top and bottom casing bars 5 and 6 respectively. 75 These bars are preferably of tubular formation, and may be of rectangular cross section as shown, and have in the side walls thereof which face each other a longitudinal slot 7. Along one edge of this slot each 80 bar is provided with suitable screen securing means 8, which coöperates with the means 4 on the vertical bar 3 to support the wire mesh M, which latter is preferably provided at its raw or cut edge with a suitable edge binding or covering 9.

As will be clear from the drawings, the bars 5 and 6 of the screen section 1 are adapted to telescopically receive the top and bottom bars 10 and 11 respectively of the 90 section 2. These bars are also of channeled formation, and are preferably substantially U-shaped in cross section, and with respect to each other bear a reversed relation, so that the open side thereof faces the inside face 95 of the bottom wall of the inclosed casing bars 1 and 2 to thereby provide a complete housing for the friction reducing elements or balls 12 which are caged therebetween. This section 2 also includes a wire mesh M' 100 which is secured to the vertical bar 13 as indicated at 14, and is also secured to the top and bottom bars 10 and 11 respectively as shown at 15. Like the mesh or screen M, the raw edge of the mesh M' is also 105 provided with a protecting edge binding 16. In connection with the mesh M' of the section 2, it will be observed that the same is secured to the bars 10 and 11 by the beading 15 in such a way that the latter may 110 freely slide in the longitudinal slots 7 of the bars 5 and 6, as clearly shown in Fig. 2.

Thus, it will be apparent that the screen sections 1 and 2 may be relatively shifted with ease and facility to suit the size of the window.

5 From the foregoing, it will be apparent that the edge bindings 9 and 16 of the screen meshes will more or less closely contact with the screen or wire mesh of the opposite section, thus providing a relatively close or
10 tight fit between the screen members at the points where they overlap. It will also be clear that the section 2 may be readily telescoped within the section 1 to vary the lateral dimensions of the screen, with ease and
15 facility, owing to the presence of the balls 12 caged between the channelled bars of the section 2 and the bottom of the casing bars of the section 1. As the telescoping parts are made of metal they will not be affected by
20 dampness or like weather conditions, and with the aid of the balls 12 will freely slide at all times, thus eliminating much of the inconvenience incident to screens of this type now in general use. The present construction
25 also provides for effectually housing and concealing the friction reducing balls, thereby preventing their loss and adding to the practicability and usefulness of the invention, and in order to provide against any
30 of the balls being withdrawn from the bars 5 and 6 when the sections are extended to their limit, the said bars may be provided with any suitable means for this purpose, as for instance, by a tongue 17 struck up from the
35 bottom wall of the bars, as shown in Fig. 4, or equivalent means.

Without further description, it is thought that the many features and advantages of the present invention will be readily apparent, and it will also be understood that various changes in the form, proportion, and minor details of construction may be resorted to without departing from the spirit of the invention or scope of the appended
45 claims.

Copies of this patent may be obtained for five cents each, by addressing the "Commissioner of Patents, Washington, D. C."

I claim:

1. A window screen construction including telescoping sections, one of said sections comprising a frame having top and bottom casing bars provided with slots and carrying a screen, and the other of said sections comprising a frame having reversely disposed channelled top and bottom bars slidable in the casing bars and also carrying a screen which is adapted to slidably overlap with the screen of the other section by working in the slots of the casing bars, and friction reducing balls between the channelled bars and casing bars. 50

2. An extensible window screen construction including slidable frame sections, one of said sections having hollow top and bottom casing bars provided with slots opening toward each other, and a screen carried by said section at one side of said slots, the other of said sections having reversely disposed channelled top and bottom bars, and also carrying a screen, and friction reducing means interposed between the channelled bars and the casing bars. 60

3. An extensible window screen construction including slidable frame sections, one of said sections having hollow top and bottom casing bars provided with slots opening toward each other, and a screen carried by said section at one side of said slots, the other of said sections having reversely disposed channelled top and bottom bars telescoping within said casing bars and also carrying a screen adapted to slide in the slots 75 of the casing bars and slidably overlap with the screen carried thereby, and friction reducing balls interposed between the channelled bars and the casing bars. 80

In testimony whereof I hereunto affix my 85 signature in the presence of two witnesses.

HAROLD A. ELDREDGE.
